UNITED STATES PATENT OFFICE

2,295,576

CLEANING APPARATUS

Wiltie I. Gladfelter, Baltimore, Md., assignor to
 Crown Cork & Seal Company, Inc., Baltimore,
 Md., a corporation of New York

Application April 9, 1941, Serial No. 387,757

17 Claims. (Cl. 91—59)

In the manufacture of various types of containers, such as beer cans having pouring openings adapted to be sealed by crown caps, the containers are usually lined with liquid coating materials, such as wax compositions. After the containers are internally coated, the excess coating material is permitted to drain from the pouring openings while the containers are in inverted position in a drain oven or the like. As a result of the draining operation, a drop or film of wax often collects on the end face of the neck finish, surrounding the pouring opening. After the draining operation has been completed, the containers are often reverted to upright position and passed through another heating oven, to permit the coating material at the bottom end to settle into and around the double seam between the bottom end member and the container side wall. If a drop or substantial film of wax is present on the neck finish end of the container, it will tend to run down the side of the neck and upon the upper, conical end of the container, with the result that the appearance of the container is adversely affected, and a messy finished product is produced.

The principal object of the invention is to provide an improved method and machine for removing and wiping the excess wax or other coating material from the neck finish ends of such containers, so that a clean sealing surface will be produced and no coating material will be present in position to run down upon the adjacent portions of the container, or otherwise disfigure the finished product.

The machine of the present invention is a modification of and improvement upon the apparatus shown in the copending application of Gladfelter, Serial No. 398,722, filed December 11, 1939. The present invention has, in general, the same objects as are set forth in the specification of the foregoing application.

A further object of the invention is to provide a machine wherein the containers are supported non-rotatably in cradles or brackets while the wiping operation is performed. With containers of certain types, it has been found to be a better practice to refrain from rolling or otherwise rotating them as they pass through a wiping machine, and the present invention provides new and improved devices for effectively cleaning the end faces and side walls of the neck finish ends of the containers while they are moved non-rotatably through the machine.

It is a further object of the invention to provide means for causing a wiping apron to engage

the end face and side walls of the neck finish end of a container simultaneously.

A further object of the invention is to provide a machine that will handle a line of containers with the same speed and facility as other machines in a container fabricating line, so that no delay in production is occasioned by the addition to the line of a neck wiping machine.

A further object of the invention is to provide improved wiping-material handling and tensioning means, whereby a supply of such material is always presented in an improved manner to the articles.

A further object of the invention is to provide novel means for removing any excess wax in the form of drops or strings from the necks of the containers before they are thoroughly cleaned by the wiping apron.

Other and further objects and advantages of the invention will be apparent to those skilled in the art from a consideration of the following description of the specific embodiment shown in the accompanying drawings, in which:

Figure 1 is a rear elevational view of the machine.

Figure 2 is a vertical section and elevation taken on line 2—2 of Figure 1.

Figure 3 is an enlarged view of one bracket and one wiping plunger assembly.

Figure 4 is a similar view, showing the parts in a different position.

Figure 5 is a fragmentary elevation of the parts shown at the right of Figure 1, on an enlarged scale.

Figure 6 is an elevational view on an enlarged scale of a friction brake for the end of the wiping apron roll shaft.

Figure 7 is a similar view of the pinch roll mounting means, and

Figure 8 is a diagrammatic view of the drive for the various rolls.

The apparatus of the present invention is designed to operate upon containers, each having a drawn seamless body, a bottom end member double-seamed to one of its ends and a neck finish formed at the other end. Such containers, for example, are shown and described in detail in the copending application of Calleson et al., Serial No. 334,876, filed May 13, 1940. As pointed out in the copending application of Gladfelter & Schmidt, Serial No. 350,976, filed August 23, 1940, containers of this kind are first preheated, then coated internally with wax and then passed, in inverted position, through a wax drain oven where the excess coating material is permitted

to drain. Thereafter, the containers are reverted to upright position and are passed through a wax settling oven.

The apparatus of the present invention is preferably positioned in the line of movement of the containers as they emerge from the wax drain oven, carried by the conveyor chain associated with that oven and before the containers are transferred to the wax settling oven conveyor. The machine functions to wipe the neck finish ends of the containers before they are brought to upright position.

The containers 10 are carried by cradles 11 having yoke members 13 pivoted at 15 to their forward ends. The yokes have cam following rollers 16 associated therewith and similar rollers 16' are carried by the brackets themselves. The cradles are pivotally connected at 17 to brackets 18 which are attached by wings 19 to the wax drain oven conveyor chain 20. The brackets 18 carry supporting and guiding rollers 21, 22 disposed in operative relation to tracks 23, 24.

As explained in the copending application of Gladfelter & Erlich, Serial No. 405,866, filed August 7, 1941, the containers are transferred from the inside waxing machine to the cradles 11 in inverted position, the cradles at that time being at their lower limit of downward swinging movement. As the containers emerge from the exit end of the wax drain oven, the brackets 11 are swung upwardly to the horizontal position shown in Figures 1 and 2 by cam rail 16a, so that their neck ends may be effectively cleaned by the apparatus of this invention. As the containers pass from this machine, the cradles 11 are swung upwardly to the vertically disposed, upright position, where they are released from the cradles by upward swinging movement of the yoke 13 and transferred to the cables of the wax settling oven, not shown herein, but fully described in the last-mentioned application.

As pointed out above, special means are provided for removing any relatively large drops or other bodies of wax before the cans enter the wiping machine proper. As illustrated in Figures 1 and 5, an upwardly projecting flue 25 has its open upper end disposed below the path of movement of the neck finish ends 26 of the containers. A gas supply pipe 27 leads to a burner 28 in the flue, so that hot gases are constantly issuing from the flue, to raise the temperature of any wax coating material that may have collected in drop form on the lowermost points of the sealing beads 26 of the containers.

Above the flue 25 and in alignment with the ends of the containers, there is an air jet 29, adapted to direct a blast of air upon the neck finish ends of the containers, to remove the heated drops of wax. The drops fall downwardly into the flue 28 and may be collected in a suitable receptacle positioned adjacent the lower end thereof.

The wiping apparatus is carried by vertical posts 30, 31 supported in pedestals 32, 33 and interconnected at their upper ends by rods 34, 35 secured in suitable apertures in the ends of brackets 36, 37. Lower brackets 38, 39 and upper brackets 40, 41 are also carried by the posts 30, 31, for purposes hereinafter described.

The horizontal rods or bars 34, 35 carry bosses 42, 42' associated with transverse bearing sleeves 43, 43' in which shafts 44, 45 are journalled, the shafts having, at their forward ends, sprockets 46, 47 fixed thereon, for rotation in a vertical plane. A sprocket chain 50 having plunger as-

semblies 51 secured to alternate links, is trained about the sprockets 46, 47, the upper run of the chain being disposed between tracks 53, 54 carried by forwardly and upwardly extended portions 55 of the brackets 36, 37.

Each plunger assembly 51 (Figs. 3 and 4) comprises a sleeve 56 bolted to wings 57 carried by the alternate links of the chain 50. The undersurfaces of the sleeves are flattened and shouldered to provide surfaces 58, 59 adapted to engage and slide along upon the upper surfaces and the inner side faces of the tracks 53, 54. Hence, the plunger assemblies 51 move along the tracks 53, 54 in predetermined spaced relation and at a predetermined speed under the influence of rotation of the sprockets 46, 47. The containers in the cradles 11 move along a predetermined path in parallel relation to the upper run of the plunger assemblies on the chain, with their neck ends 26 aligned with the assemblies, means being provided, as hereinafter explained, to cause the conveyor chain and the plunger assembly carrying chain 50 to move in unison, at the same speed.

The chain 20, at its rear end, at a point beyond 25 the station where the containers are transferred to the wax settling oven conveyor, is trained about a sprocket 60 (Fig. 1) secured to the upper end of a shaft 61 journalled in brackets secured to an appropriate support. At its lower end the shaft 61 carries a sprocket 62 connected by a chain 63 to a sprocket 64 journalled on a stub shaft, not shown, carried by the upper end of a pedestal 65. That stub shaft carries a second sprocket connected by a chain to a sprocket 66, fast on a main drive shaft 67, journalled at its lower end in a bearing 68 associated with a bracket 69 carried by post 31, and at its upper end in a gear box 70, carried by the transverse bearing sleeve 43'. The shaft 67 has a bevelled gear at its upper end disposed within the gear box 70, in mesh with a similar gear on the transverse shaft 45, journalled in bearing sleeve 43', whereby rotation is imparted to the shaft 45, to drive the sprocket 47, the chain 50 and the sprocket 46 at the same speed as the chain 20.

The upper brackets 40, 41 carry, at their rear ends, upwardly projecting members 75, 76 having seats adapted to support brake assemblies which receive the ends of a shaft 77 upon which an elongated sheet of wiping material, such as a cloth apron, is wound in the form of a roll 78. The brake assemblies each comprise lower halves 79 and upper halves 80, the latter being urged downwardly by springs 81 upon the ends of the shaft, to produce a suitable friction drag.

The wiping apron 78' is led from the roll supply over a guide roll 82 having its ends journalled in forward extensions of the brackets 40, 41. A cooperating pinch roll 83 is journalled at its ends in links 84, pivoted to the brackets at 85. The roll is urged downwardly into firm contact with the roll 82 by clamps 86, each pivoted upon the upper end of a vertically adjustable bolt 87, and being provided with a cam nose 88.

The apron passes downwardly over the lower pinch roll 82 in a substantially vertical run 99, between the ends of the containers and the ends of the plunger assemblies 51. At the lower end of this run, it is guided rearwardly between a pair of pinch rolls 82', 83', similar to the first-mentioned pair of rolls. The roll 83' is urged upwardly into contact with the sheet material by a similar clamp 86'.

A pair of relatively small rollers 95, 96 are supported upon the lower brackets 38, 39, above and

behind the rolls 82', 83'. The rollers 95, 96 are positively driven, as hereinafter explained, and make peripheral contact with a roll 97 of sheet material, wrapped upon a core 98, to rewind the soiled wiping apron, the ends of the core 98 being disposed in openings 99 in vertical guideways 100.

The apron is slowly unwound from the roll supply 78 by the positively driven pinch rollers 82, 83, against the frictional resistance applied to the roll by the brake elements 79, 83. The apron is drawn downwardly through the run 90 by the positive pinch rollers 82', 83', and is rewound by the rollers 95, 96, both of which, preferably, are positively rotated, as hereinafter explained.

The shaft 44, driven by the sprocket 46, carries a small sprocket 105 on its rear end, connected by a chain 106 to the driving sprocket 107 of a speed reducer 108, having a driven sprocket of relatively small diameter 109 associated therewith. The latter is connected by a chain 110 to a sprocket 111 on a stub shaft 112 carried by a bracket 113 secured to the vertical post 39. The stub shaft carries a second sprocket 114 having a chain 115 trained thereabout and around an idler sprocket 116 and a sprocket 117 on the shaft of roller 82'. This chain 115 is also in mesh with a sprocket 118 on the adjacent end of the roller 95. Hence, rotation is imparted from the sprocket 114 by the chain 115 to the rewinding roller 95 and to the pinch rolls 82', 83'. The rollers 95 and 96 are interconnected at their other ends by a short chain 119 trained about sprockets 95', 96', so that they rotate in the same direction in unison.

Another sprocket 119 is fixed upon the stub shaft 120 for the idler sprocket 116. A chain 121, trained about the periphery of sprocket 119, drives a similar sprocket 122 fixed upon a stub shaft 123, carried by the upper bracket 40. A chain 124, trained about a second sprocket 125 on the stub shaft 123, is connected to a sprocket 126 on the upper pinch roll 82, whereby rotation is imparted to the rolls 82, 83.

As a result of the drive just described, the wiping apron is slowly fed in a downward direction between the ends of the containers and the wiping plunger assemblies and is then rewound. Hence, a desired speed of movement is imparted to the cloth, so that a single roll may last for a full eight-hour shift, or longer. Moreover, the apron is maintained under the desired tension at all times by the positively driven pinch rolls and the friction brake associated with the supply.

The wiping plungers and their operating means will now be described. The brackets 38, 37 carry upwardly projecting supporting members 130, 131, which support a horizontally disposed cam rail 132 having a forwardly projecting elongated portion 133 terminating in inclined ends 134. The sleeves 56 of the plunger assemblies have internal bores therein, provided with enlarged portions 135 at their rear ends, and of restricted diameter 137 at their forward ends. Disposed in each bore is a plunger shaft 138 having an enlarged rear end 139 constituting an abutment for a coil compression spring 140, the other end of which bears against the forward end of the enlarged bore 135. The rear end of the enlargement 139 terminates in a projection 142, adapted to engage the face of the cam rail 132. The forward end of the plunger shaft carries a special socket member 145 having a concave end

face defined by an end wall 146 and a circular internal side wall 147, these surfaces being adapted to be disposed opposite to the end face and the side wall of the neck finish end of the associated container, with the wiping apron interposed therebetween.

As the containers and plunger assemblies move jointly across the apron, on opposite sides thereof, the cam rail 132 projects the plungers forwardly from the position shown in Figure 3 to that of Figure 4, so that the neck ends of the containers are inserted to the desired extent into and are embraced by the concave, socketed ends of the plungers with the apron interposed therebetween, as clearly shown in Figure 4. The parts in this position move horizontally relative to the apron, with the result that successive portions of the apron are forced to flow into and out of the socketed end of the plunger in wiping relation to the entire neck finish of the container, including the end and the terminal portions of the side surfaces thereof. Since the apron is moved transversely with respect to the line of movement of the containers, although quite slowly, substantially fresh wiping surfaces are continually presented to the successive containers.

As a result of this construction, rotation of the containers is unnecessary. Moreover, an improved, positive wiping action of the desired surfaces is effected, by the partial or substantially complete insertion of the ends of the containers into the concave ends of the plungers, with the wiping apron interposed.

Many modifications of the machine shown in the accompanying drawings and of the method of the present invention will readily occur to one skilled in the art and all such modifications as come within the scope of the appended claims are intended to be included within the invention.

I claim:

1. An apparatus for wiping the ends of articles such as containers comprising means for moving the articles along a predetermined path, a wiping apron disposed along one side of said path facing the ends of the containers to be wiped, means on the opposite side of the apron from the containers mounted for movement with the containers along a path parallel therewith, and means for projecting the last-mentioned means toward the apron and the containers to move the apron into wiping relation to the ends of the containers as they move along said path.

2. An apparatus for wiping the ends of containers or the like comprising means for supporting the containers in non-rotatable relation and for moving the same along a predetermined path while so supported, a wiping apron disposed along said path and facing the ends of the containers to be wiped, a plurality of plungers positioned behind the apron, movable with the containers and having their ends aligned with the ends of the containers to be wiped, and cam means for projecting said plungers toward the apron and the containers, to urge the apron into wiping contact with the containers.

3. An apparatus for wiping the ends of containers, comprising means for moving the containers along a predetermined path transverse to their longitudinal axes, a wiping apron disposed along one side of said path, means on the opposite side of the apron having concave surfaces facing the ends of the containers, means for relatively converging the ends of the containers and said surfaces to guide the apron into embracing relation to the ends of the containers as

the latter move relative to the apron, and means for shifting the apron transversely to the line of movement of the containers to present substantially fresh surfaces thereto.

4. An apparatus for wiping the ends of containers, comprising means for moving a line of containers in horizontal position along a horizontal path transverse to their axes, a wiping apron having a vertically disposed portion facing the ends of the containers, means on the opposite side of the apron having concave surfaces facing the ends of the containers, means for relatively converging the ends of the containers and said surfaces to guide the apron into embracing relation to the ends of the containers as the latter move relative to the apron, and means for vertically shifting the apron to present substantially fresh surfaces to successive containers.

5. An apparatus for wiping the neck finish ends of containers comprising means for moving the containers along a predetermined path transverse to their longitudinal axes, a wiping apron facing the ends of the containers, and means behind the apron, mounted for movement along said path with the containers and for axial movement toward said ends and having surfaces positioned to cause the apron simultaneously to embrace the end faces and circumferentially continuous end portions of the side walls of the neck finish ends of the containers as the containers and the last-mentioned means move relative to the apron.

6. An apparatus for wiping the neck finish ends of containers, comprising means for moving the containers along a predetermined path and for supporting them against rotation during such movement, a wiping apron adjacent said path, and means on the opposite side of the apron having concave surfaces aligned with the ends of the containers and movable toward the containers and with the containers to guide the apron into wiping engagement with the end face of the neck finish ends and simultaneously therewith into circumferentially continuous wiping engagement with the terminal portions of the side walls of the neck finish ends of the containers.

7. An apparatus for wiping the neck finish end of a container, comprising means for supporting the container, a member having a surface facing the end wall of the neck finish end and another surface disposed in concentric relation to and opposite the side wall thereof when in operative relation thereto, a wiping apron disposed between said surfaces of said member and said walls, means for relatively moving the member and the container toward each other to cause the neck finish end of the container to assume said operative relation with the end and side walls thereof in engagement with the apron, and means for moving the neck finish end of the container relative to the apron while in such position.

8. An apparatus for wiping the neck ends of containers, comprising a conveyor chain, a plurality of brackets carried by the chain adapted to hold the containers in non-rotatable relation and to move the same along a predetermined path in substantially horizontal position, a second conveyor chain having a run in parallel relation to the first-mentioned chain, a plurality of plungers carried by the second chain having ends aligned with and facing the neck ends of the containers, a wiping apron interposed between the container ends and the plunger ends, and cam means for projecting the plungers toward the apron and the containers, whereby the apron

wipes the container ends as the containers and the plungers move relative to the apron.

9. An apparatus for wiping the neck ends of containers, comprising a conveyor chain, a plurality of brackets carried by the chain adapted to hold the containers in non-rotatable relation and to move the same along a predetermined path in substantially horizontal position, a second conveyor chain having a run in parallel relation to the first-mentioned chain, a plurality of plungers carried by the second chain having concave ends aligned with and facing the neck ends of the containers, a wiping apron interposed between the container ends and the plunger ends, and cam means for projecting the plungers toward the apron and the containers to cause the neck ends of the containers and the apron to enter the concave plunger ends, whereby the apron wipes the container ends as the containers and the plungers move relative to the apron.

10. An apparatus for wiping the neck ends of containers, comprising a conveyor chain, a plurality of brackets carried by the chain adapted to hold the containers in non-rotatable relation and to move the same along a predetermined path in substantially horizontal position, a second conveyor chain having a run in parallel relation to the first-mentioned chain, a plurality of plungers carried by the second chain having concave ends aligned with and facing the neck ends of the containers, a wiping apron interposed between the container ends and the plunger ends, cam means for projecting the plungers toward the apron and the containers to cause the neck ends of the containers and the apron to enter the concave plunger ends, whereby the apron wipes the end faces and side wall portions of the container ends as the containers and the plungers move relative to the apron, and means for shifting the position of the apron relative to the line of containers and plungers to present a substantially continuously changing apron surface thereto.

11. An apparatus for wiping the ends of containers, comprising means for supporting a supply of sheet material in roll form, a pair of guiding and pinching rolls for drawing the sheet from the supply, a second pair of similar rolls spaced from the first pair and adapted to receive the sheet therefrom and to stretch the sheet in a predetermined plane, means for receiving the sheet from the second pair of rolls and for rewinding the same, means for moving the containers along one side of the stretched sheet, and means on the opposite side thereof for projecting the sheet into wiping contact with the ends of the containers as they move relative thereto.

12. An apparatus for wiping the ends of containers, comprising two pairs of pinch rolls disposed on horizontal axes in vertically spaced relation, means for feeding a sheet of wiping material successively between the pairs of rolls under predetermined tension, means for moving a line of containers horizontally with their neck ends facing the vertical run of the sheet, and means on the opposite side of the sheet moving with the containers for projecting the sheet into wiping contact with the adjacent ends of the containers.

13. An apparatus for wiping the ends of containers, comprising two pairs of pinch rolls disposed on horizontal axes in vertically spaced relation, means for feeding a sheet of wiping material successively between the pairs of rolls under predetermined tension, means for moving a line of containers horizontally with their neck ends

facing the vertical stretch of the sheet, a plurality of plungers having concave end faces disposed behind the sheet and moving with the containers, and means for relatively converging the end faces of the plungers and the neck ends of the containers during their joint movement to cause the latter to be inserted in and to be embraced by the concave plunger end faces with the sheet material interposed between.

14. In a machine for wiping the neck finish ends of containers, a wiping apron having a vertically disposed portion, means for moving a line of containers in horizontal position along one side of the apron, a pair of sprockets journalled for rotation in a vertical plane on the opposite side of the apron, a chain trained about the sprockets and having one run parallel with the line of movement of the containers, a plurality of plungers carried by the chain and aligned with the ends of the containers, and means for projecting the plungers forwardly to urge the apron into wiping contact with the containers.

15. In a machine for wiping the neck finish ends of containers, a wiping apron having a vertically disposed portion, means for moving a line of containers in horizontal position along one side of the apron, a pair of sprockets journalled for rotation in a vertical plane on the opposite side of the apron, a chain trained about the sprockets and having one run parallel with the line of movement of the containers, a plurality of sleeves carried by the chain aligned with

the containers, plungers in the sleeves, spring means urging the plungers rearwardly, and cam means adapted to project the plungers toward the apron to urge the latter into wiping contact with the containers.

16. In a machine for wiping the neck finish end of a container, a wiping apron, means for supporting a container on one side thereof with the neck finish end facing the apron, and a plunger assembly on the other side of the apron adapted to move the apron into wiping contact with the container end, said assembly comprising a sleeve, a shaft slidably mounted in the sleeve, a socket member at the end of the shaft facing the apron, a spring for retracting the shaft and member to an inoperative position, and cam means for projecting the shaft and member toward the apron.

17. In a machine for wiping the neck finish ends of containers, a vertically disposed wiping apron, means for moving a line of containers with their neck finish ends facing the apron, a sprocket chain on the other side of the apron, a pair of trackways along opposite sides of the chain, a plurality of sleeves carried by the chain and slidably mounted on the trackways, plungers carried by the sleeves, and a stationary cam for projecting the plungers toward the apron to urge the latter into wiping contact with the neck finish ends of the containers.

WILFIE I. GLADFELTER.
